CLAIM

The ornamental design for a multifunction bench vice, as shown and described.

DESCRIPTION

FIG. 1 is an upper perspective view of the multifunction bench vice showing my design in a first configuration.

FIG. 2 is another upper perspective view thereof, in a second configuration;

FIG. 3 is a side elevation view of the second configuration of FIG. 2;

FIG. 4 is an opposite side elevation view of the second configuration of FIG. 2;

FIG. 5 is an end elevation view of the second configuration of FIG. 2;

FIG. 6 is an opposite end elevation view of the second configuration of FIG. 2;

FIG. 7 is a top plan view of the second configuration of FIG. 2; and,

FIG. 8 is a bottom view of the second configuration of FIG. 2.

The broken line showing of parts of the drawings is included for the purpose of illustrating use and environment and forms no part of the claimed design.

The multifunction bench vice has a first configuration with a first gripping means in a top position and a second gripping means in a bottom position and a second configuration with the second gripping means in the top position and the first gripping means in a bottom position.
